DESCRIPTION

In a preferred embodiment, the nature of this product is a
plumbing fitting in the form of a body for a kitchen faucet.

FIG. 1 is a left, top, front perspective view of a faucet body
according to our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a right, top, front perspective view of a faucet body
according to another embodiment of my new design, the
front, left side, right side and rear elevational views thereof
and the top and bottom plan views thereof being mirror
images of the views shown in respective FIGS. 2-7.

The broken line representations in the figures are for the
purpose of illustration only, and form no part of the claimed
design.
